UNITED STATES PATENT OFFICE.

LEO STEIN, OF ROCHESTER, NEW YORK, ASSIGNOR TO THE STEIN MANUFACTURING COMPANY, OF SAME PLACE.

DESIGN FOR A BURIAL-CASKET LID.

SPECIFICATION forming part of Design No. 17,218, dated March 29, 1887.

Application filed January 6, 1887. Serial No. 223,623. Term of patent 14 years.

To all whom it may concern:

Be it known that I, LEO STEIN, of Rochester, in the county of Monroe, in the State of New York, have invented a new and useful Design 5 for Metallic Burial-Casket Lids, of which the following, taken in connection with the accompanying drawings, is a full, clear, and exact description.

My invention relates to designs for metallic-10 coffin or burial-casket lids; and the invention consists in the herein-described design, which will be described in connection with the accompanying drawings, and pointed out in the claim.

15 Figure 1 is a top plan view of my newly-designed metallic coffin-lid. Fig. 2 is a transverse section taken on line $x-x$, Fig. 1, and Fig. 3 is a side elevation of the same, these three views being deemed necessary to fully 20 illustrate my design.

The leading feature of my design consists in a gracefully-curved or oval-shaped foot portion rising gradually from the rim to the highest point of the curve in easy and pleasing 25 lines, as best shown in the sectional view, Fig. 2.

A represents the metallic lid, composed of the head-section B and foot-section C, having respectively the rounded ends $b-c$ and the rim 30 a , extending around the entire edge of the lid. The head-section portion B is flat, as best

shown in Figs. 1 and 3, while the foot portion C is oval and gracefully curved from edge to edge of the rim $a-a$, as best shown in Fig. 2, while the extremity c' inclines down to the 35 rounded end c , as shown in Fig. 3. The outline of the oval surface of the foot portion falls gently from the crown or highest portion of the curve to the rim a , and, in connection with the rounded ends $b-c$ and the flat portion B, 40 presents to the eye the combined effect of a smooth curved outline from the head portion B to the inclined extremity c' and the rounded ends $b-c$.

Having thus fully described my design, what 45 I claim as new, and desire to secure by Letters Patent, is—

The design for a coffin or burial-casket lid, consisting of the flat head-section B, the foot-section C, curved or oval-shaped in cross-section, the inclined curved portion c' , and the 50 rounded ends $b-c$, substantially as shown and described.

In testimony whereof I have hereunto signed my name, in the presence of two attesting witnesses, at Rochester, in the county of Monroe, in the State of New York, this 22d day of December, 1886.

LEO STEIN.
